US0D1095744S

(12) **United States Design Patent** (10) **Patent No.:** **US D1,095,744 S**
(45) **Date of Patent:** **** Sep. 30, 2025**

(54) **ARTIFICIAL BAIT**

(71) Applicant: **SHANDONG HANDING INTERNATIONAL TRADE CO., LTD**, Weihai (CN)

(72) Inventor: **Chao Liu**, Weihai (CN)

(73) Assignee: **SHANDONG HANDING INTERNATIONAL TRADE CO., LTD**, Weihai (CN)

(**) Term: **15 Years**

(21) Appl. No.: **29/940,987**

(22) Filed: **May 7, 2024**

(30) **Foreign Application Priority Data**

Apr. 9, 2024 (CN) 202430192725.X

(51) **LOC (15) Cl.** **22-05**

(52) **U.S. Cl.**

USPC **D22/132**

(58) **Field of Classification Search**

USPC D22/125, 126, 130, 131, 132, 133;

43/42, 42.1, 42.21

CPC A01K 85/00; A01K 85/005; A01K 85/021;

A01K 85/14

See application file for complete search history.
